UNITED STATES PATENT OFFICE.

THOMAS J. THORP, OF CORVALLIS, OREGON.

WHEEL.

No. 912,758.

Specification of Letters Patent.

Patented Feb. 13, 1909.

Application filed June 21, 1907. Serial No. 380,085.

To all whom it may concern:

Be it known that I, THOMAS J. THORP, a citizen of the United States, residing at Corvallis, in the county of Benton and State of Oregon, have invented a new and useful Improvement in Wheels, of which the following is a specification.

My invention relates particularly to wheels involving in the structure thereof the use of structural metal; and my primary object is to provide a strong and durable wheel of moderately light construction and provided with an improved tread.

The invention is illustrated in the accompanying drawing, in which—

Figure 1 represents a broken side elevational view of my improved wheel (partly in section); Fig. 2, a broken plan view or tread-view of the same; Fig. 3, a broken section taken as indicated at line 3 of Fig. 1 and showing details of the hub construction; Fig. 4, a broken section taken as indicated at line 4 of Fig. 1; Fig. 5, a broken side elevational view (partly in section) of a modified form of the invention; and Fig. 6, a view partly in plan and partly in section, taken as indicated at line 6 of Fig. 5.

In the construction illustrated in Figs. 1 to 4 inclusive, A represents a sectionally constructed hub; B loop-shaped spokes having their inner ends connected with said hub; and C, a sectionally constructed rim and tread. The hub A comprises a sleeve or barrel a^1 provided centrally upon its exterior with a rigid collar a^2 ; hub-sections a^3 , a^4 seated on said barrel a^1 and recessed interiorly to accommodate the collar a^2 , the adjacent faces of said hub-sections a^3 , a^4 being provided with recesses a^5 adapted to receive the inner ends of the spokes; and bolts a^6 connecting said hub-sections. The adjacent faces of the hub-sections a^3 , a^4 do not quite meet, the inner ends of the spokes being clamping received in the recesses a^5 . Each spoke B preferably comprises a loop-form or triangular-shaped member formed by bending a bar of T-shaped cross-section into the form shown, thus affording substantially radial members b^1 and a connecting web b^2 at the outer ends thereof. In forming the spoke, the web b^2 is disposed so as to lie within the loop of the spoke. The inner extremities of the members b^1 are bent, as indicated at b^3 , so as to be received by the obliquely-disposed recesses a^5 of the hub-sections, so

that the inner ends of the spokes will be firmly anchored to the hub-sections. The outer ends or base-portions of the loop-form spokes are secured to a metal rim c^1 ; and applied to the rim c^1 are tread-blocks c^2 , which preferably are composed of wood in which the grain runs in a direction substantially radial with relation to the wheel. The tread-blocks are secured to the rim by bolts c^3 which have block-form heads c^4 which are beveled on their edges, as indicated at c^5 . Alternate meeting edges of the tread-blocks are beveled as indicated at c^6 to receive the block-form ends of the bolts, as clearly appears from Fig. 2; and alternate meeting edges of said tread-blocks are provided with recesses c^7 having beveled surfaces receiving said block-form heads of bolts, as also appears from Fig. 2. The blocks are preferably so disposed as to afford at the alternate meeting edges thereof recesses or spaces c^8 which serve the function of roughening or breaking the tread-surfaces, so that the tread will take firm hold on the ground. Obviously, the bolts may be tightened to accommodate for shrinkage or wear of the tread-block.

In the construction shown in Figs. 5 and 6, the same general idea is employed. In this construction the sectional hub is designated A^1 ; there are two series of spokes B^1 , B^2 ; and the wheel-rim and tread is designated C^1 . The hub A^1 comprises a barrel a^6 ; intermediate hub-sections a^7 flanking a centrally-located exterior collar with which said barrel is provided; outer hub-sections a^8 ; and connecting bolts a^9 . The hub-sections a^7 , a^8 are recessed to receive the inner ends of the two series of spokes, as will be understood from Fig. 6. Each spoke B^1 is preferably of loop-form or triangular form, comprising an angle-bar bent to form a substantially radial member b^4 and the web-portion b^5 , the inner ends of the members b^4 being bent somewhat and received by the recesses of the hub-sections. Applied to the spokes is a broad rim c^8 over the lateral margins of which are placed narrow circular bands c^9 ; and tread-blocks c^{10} are applied to the rim c^8 , said tread-blocks being recessed at their ends on their inner surfaces to accommodate the bands c^9 . The tread-blocks are provided with lateral recesses c^{11} which are located near their ends and which have beveled surfaces which receive the cor-

responding beveled surfaces of block-shaped heads of bolts c^{12} , by means of which the tread-blocks are secured to the rim c^8 and bands c^9 . Alternate meeting edges of the tread-blocks are separated slightly to afford spaces c^{13} which enable the wheel to take good hold upon the ground. The flanges of the spokes B^1 are so disposed as to provide bearings d at the ends of the tread-blocks, these bearings being rounded as indicated at d^1 in the curvature of the spoke. It will thus be understood from Figs. 5 and 6 that the bearings d are arranged concentrically with the tread-surface and somewhat within the circle of the tread-surface, so that when a vehicle is turned out of a street railway-track, for instance, the bearings d will ride on the rail and enable the wheel readily to rise from the groove of the rail, the curved shoulders d^1 aiding in this function.

The construction last described is exceedingly strong and durable being adapted to very heavy work. In both constructions, the strength in proportion to the lightness is noteworthy; and, in each, provision is made for tightening the tread-blocks in case of shrinkage. Moreover, in each construction provision is made for an effective engagement of the tread with the earth.

What I regard as new and desire to secure by Letters Patent, is:

1. A wheel, comprising a hub and tread, and spokes having portions at their outer

ends which flank the wheel-tread and afford bearings arranged in a circle of less diameter than that of the outer surface of the wheel-tread, thus affording bearings adapted to engage a rail and aid the wheel in leaving a track, for the purpose set forth. 35

2. A wheel, comprising a rim, a sectionally constructed hub, a series of spokes at each side of the wheel, each spoke being of loop-form with the extremities of its members secured in said hub and with its loop end provided with a portion projecting past 45 said rim, and tread-blocks secured to said rim between the projecting portions of said spokes, for the purpose set forth. 40

3. A wheel, comprising a rim, a sectionally constructed hub, a series of spokes at 50 each side of the wheel, each spoke comprising an angle-bar bent into loop-form, the inner extremities of the members of the spoke being secured to said hub and one flange of the loop end of the spoke lying within said 55 rim and the other flange projecting past said rim, relatively narrow bands encircling the rim at the edges thereof, tread-blocks recessed on their inner surfaces to fit over said bands, and clamping-bolts engaging adjacent ends of said tread-blocks and extending through said rim. 60

THOMAS J. THORP.
